UNITED STATES PATENT OFFICE.

FREDERICK DANNER, OF TARENTUM, PENNSYLVANIA.

ANNEALING-FURNACE.

SPECIFICATION forming part of Letters Patent No. 694,054, dated February 25, 1902.

Application filed August 19, 1901. Serial No. 72,484. (No model.)

To all whom it may concern:

Be it known that I, FREDERICK DANNER, a citizen of the United States, residing at Tarentum, in the county of Allegheny and State 5 of Pennsylvania, have invented or discovered certain new and useful Improvements in Annealing-Furnaces, of which improvements the following is a specification.

The invention described herein relates to 10 certain improvements in leers or annealing-furnaces for plate-glass.

It has heretofore been customary to support the carriages or frames by which the plates of glass are carried through the cooling 15 portions of the furnace upon continuous rails extending longitudinally through the furnace, the frames or carriages being provided with wheels, which ride along on the rails. These constructions are objectionable on account of the liability to twisting of the long 20 rail by variations of heat in different parts, so that the glass is not uniformly supported during its entire traverse through the furnace.

The object of the present invention is to provide 25 a suitable carrying-frame for the glass and means for supporting the latter during its movement, said parts being so constructed and arranged as to avoid all liability of any distortion of any of the parts.

30 The invention is hereinafter more fully described and claimed.

In the accompanying drawings, forming a part of this specification, Figure 1 is a sectional elevation of a portion of a leer, the 35 plane of section being indicated by the line I I, Fig. 3. Fig. 2 is a horizontal section on a plane indicated by the line II II, Fig. 3. Fig. 3 is a transverse section on a plane indicated by the line III III, Fig. 2. Figs. 4 and 40 5 are detail views illustrating the glass-carrying frame.

In the practice of my invention the furnace is constructed as regards the preliminary heating sections or chambers 1, 2, and 3 in the 45 usual or any suitable manner, said chambers being so located and having their bottoms so constructed on a common plane that the plates of glass may be shoved from one to the other in the usual manner. The tunnel 4 is arranged, preferably, at right angles to the direction of movement of the glass through the chamber 3. A series of shafts 5 are arranged

transversely of the tunnel, their end portions being supported in bearings 6, which are preferably provided with anchor plates or extensions 7, embedded in the side walls of the tunnel, as clearly shown in Fig. 3. On these shafts 5 are mounted supporting-wheels 8, having flanges to properly guide the supporting-frames in their passage through the furnace. These supporting-frames consist of rails 9, preferably similar to railroad-rails, but inverted, so that their heads will rest upon the wheels 8. To the flanges of the rails 9 are secured supporting-bars 10, said bars being preferably of a T shape in cross-section and so secured to the rails that the same portion of the bars will extend upwardly and form the bearings of the glass plate to be annealed. These supporting-bars can be arranged in close proximity to each other, and thereby afford ample supporting-surface, while only small portions of such surface are in contact with any portion of the plate of glass. The frames are designed to be connected one to the other by any suitable form of coupling—such, for example, as that shown—consisting of links 11 and hooks 12, arranged on opposite ends of the supporting-rails 9. The wheels 8 may be loosely mounted upon 80 their shafts, in which case the frames will be drawn through the tunnel by any suitable pulling mechanism acting continuously or intermittently as is known in the art, or the carrying-frames may be shifted through the 85 tunnel by the rotation of the wheels 8.

It is characteristic of my improvement that as the supporting-shafts 5 are arranged transversely of the furnace all portions of each shaft will be always subjected to the same 90 heat or temperature, so that there can be no differences of expansion whereby a distortion thereof may be caused. The rails 9, forming the supports or foundations for the frames, are in short sections, and hence will 95 occupy relatively short portions or distances of the tunnel, so that they will be always subjected to an approximately uniform heat at any given time. Even if subjected to differences of temperature, the rails being so short, 100 an equalization of such temperature by conduction will occur, thereby avoiding differences of expansion. Hence it will be readily understood by those skilled in the art that

the parts of the carrying-frames will always preserve a uniform relation to each other, and there can be no changes or shifting of the supporting-wheels, whereby the frames may be warped or twisted as they move through the furnace.

I claim herein as my invention—

An annealing-furnace having in combination, a tunnel, a series of shafts arranged transversely of the tunnel, supporting-wheels

adapted to turn freely carried by said shafts, rail-sections adapted to ride upon said wheels and carrying-bars secured to the rails at right angles thereto, substantially as set forth.

In testimony whereof I have hereunto set my hand.

FREDERICK DANNER.
